UNITED STATES PATENT OFFICE

WILLIAM CHESTER POPPE, OF CHICAGO, ILLINOIS.

FLASK.

1,071,175.

Specification of Letters Patent. Patented Aug. 26, 1913.

Application filed February 10, 1913. Serial No. 747,437.

To all whom it may concern:

Be it known that I, WILLIAM CHESTER POPPE, a citizen of the United States, residing at Chicago, in the county of Cook and State of Illinois, have invented certain new and useful Improvements in Flasks, of which the following is a specification.

The flask which is the subject of the present invention is designed more particularly to hold liquids which are under pressure, and its object is to provide convenient means for controlling the discharge of the liquid from the flask. The flask is so shaped, and a closure and operating means for the latter are provided, which enable the discharge to be controlled by the same hand that grasps the flask.

The invention is illustrated in the accompanying drawing in which—

Figure 1 is a plan view of the flask. Fig. 2 is a side elevation thereof. Fig. 3 is a sectional detail showing the closure.

Referring specifically to the drawing, 5 denotes the body of the flask, the same having a suitable filler opening 6 provided with a closure 7. This opening is shown in the bottom of the flask, but it may be made in any other convenient place. The flask body is tapered toward its upper or outlet end, 30 and said end is also deflected sidewise, and has a small discharge orifice 8. A siphon tube 9 is located in the flask, its lower end opening near the bottom of the flask, and its upper end tapering and entering the orifice 8.

The closure for the flask is a spherical valve plug 10 seating on the outer end of the orifice 8. This valve plug is carried by a stem 11 passing through a slit in a guard 40 12 and pivoted thereto as indicated at 13. The guard 12 is a strip which is secured at its ends to the flask body and is bowed outward therefrom similar to the trigger-guard of a fire-arm. The valve stem 11 is 45 shaped like a trigger and has connected to its end, opposite the end carrying the plug, one

of the arms 14 of a V-shaped spring, the other arm of which spring is secured to the flask body. This spring serves to hold the valve plug to its seat. Upon pressing the 50 valve stem toward the flask body the valve plug is unseated, and when the valve stem is released, the spring at once reseats the valve plug. The spring is strong enough to overcome the pressure of the contents of the 55 flask.

The action is very simple and the valve can be operated by the same hand which holds the bottle. The shape of the flask body and the position of the valve stem enables 60 the flask to be held and the valve opened in the same manner a revolver would be held, and its trigger pulled to discharge the same, the valve stem and the guard being 65 on the concavely curved side of the flask body.

I claim:

1. A flask comprising a body having its outlet end deflected sidewise and provided with a discharge orifice, a closure for said orifice, a stem carrying the closure, said stem extending toward the concavely curved side of the flask body, a guard secured to the flask body to which guard the aforesaid stem is pivoted and within which it lies, and 75 a spring for holding the closure seated.

2. A flask comprising a body having its outlet end deflected sidewise and provided with a discharge orifice, a closure for said orifice, a stem carrying the closure, said stem 80 extending toward the concavely curved side of the flask body, a guard secured to the flask body and having a slit through which the aforesaid stem passes and in which the stem is pivoted, and a spring for holding 85 the closure seated.

In testimony whereof I affix my signature in presence of two witnesses.

WILLIAM CHESTER POPPE.
